(57) **CLAIM**

The ornamental design for a power adapter, as shown and described.

DESCRIPTION

FIG. 1 is a bottom perspective view of a power adapter showing my new design, showing AC prongs of the power adapter being unfolded in a usage position;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a top perspective view thereof;

FIG. 9 is a perspective view thereof, shown in a first environmental use;

FIG. 10 is a perspective view thereof, shown in a second environmental use;

FIG. 11 is a perspective view thereof, shown in a third environmental use; and,

FIG. 12 is a top perspective view thereof, showing the AC prongs of the power adapter being folded in a storage position.

The power adapter is shown with a symbolic break in its length. The appearance of any portion of the article between the break lines forms no part of the claimed design.

The broken lines in the drawings are included for the purpose of illustrating environmental structure and forms no part of the claimed design.
